JOHN FRITH, OF BRIDGEPORT, CONNECTICUT.

ATTACHMENT FOR CONTROLLING TELEPHONE SWITCH-HOOKS.

1,082,856.

Specification of Letters Patent.

Patented Dec. 30, 1913.

Application filed November 8, 1912. Serial No. 730,194.

To all whom it may concern:

Be it known that I, JOHN FRITH, a subject of the King of Great Britain, residing at Bridgeport, county of Fairfield, State of Connecticut, have invented an Improvement in Attachments for Controlling Telephone Switch-Hooks, of which the following is a specification.

This invention has for its object to provide a telephone attachment adapted for use upon ordinary desk sets, so-called, that will permit connections to be made and broken by a simple movement of an element of the attachment and will itself hold the receiver 15 in a convenient position for use, thus doing away with the necessity of detaching the receiver and holding it to the ear during a conversation, and furthermore, what is sometimes quite important, my novel attachment leaves both hands free for use, as in holding a pad and writing upon it.

With these and other objects in view I have devised the novel telephone attachment which I will now describe, referring to the 25 accompanying drawing forming a part of this specification and using reference characters to indicate the several parts.

Figure 1 is an elevation showing my novel attachment in place upon an ordinary desk telephone, the hook being in its normal position and the circuit open as when the instrument is not in use; Fig. 2 a detail view on an enlarged scale corresponding with Fig. 1; Fig. 3 a similar view showing the 35 position of the hook and parts of the attachment when the circuit is closed and the instrument in use; Fig. 4 a detail view as seen from the left in Fig. 2, the hook being omitted; Fig. 5 a similar view as seen from 40 the right in Fig. 2, the clip being omitted, and Fig. 6 is a detail elevation on an enlarged scale showing the attaching means and adjustments of the carrying arm.

10 denotes the standard, 11 the transmitter, 12 the spring controlled hook, 13 the receiver and 14 the receiver conductors of a telephone which may be of any ordinary or preferred construction. I have shown a well-known form of hook which in ordinary

telephones is retained at the normal or open 50 circuit position (as in Fig. 1) by the weight of the receiver which is hung thereon. When the receiver is disengaged from the hook it is thrown to the raised or circuit-closing position (as in Fig. 3) in any suitable manner, as by means of a spring 15 forming part of the telephone itself. As the structure of the telephone forms no portion of the present invention, it is not thought necessary for the purposes of this 60 specification to illustrate or describe the parts by which the circuit is opened and closed. It is sufficient to say that when the hook is in its normal or lowered position, as in Figs. 1 and 2, the circuit is open and the 65 instrument out of use, and when the hook is in the raised position, as in Fig. 3, the circuit is closed and the instrument may be used.

My novel attachment requires no change 70 whatever in the telephone and may be attached to any instrument in a moment's time and without the use of tools other than a screw driver.

The attachment comprises means coöperating with the telephone hook for retaining the hook in the normal or open-circuit position and for releasing it to permit spring 15 to throw it to the operative or circuit-closing position, as in Fig. 3. The receiver 75 is adjustably secured to an arm 16 which is preferably tubular so that the receiver conductors may pass through it and which is so connected to the standard as to be free to swing in either the vertical or horizontal 80 plane.

17 denotes a clip whose arms inclose the receiver and are caused to grip it by means of an adjusting screw 18. This clip may be either rigidly or pivotally secured to a 90 sleeve 19 which is adapted to slide on the arm and is locked in any required position by a set screw 20. The other end of the arm is connected to the standard by a suitable universal joint. In the present instance the 95 arm is shown as provided with a hinge plate 21 which contacts with a similar plate on a member 22, the two plates being clamped

together to hold the arm in any position in which it may be placed by means of a screw 23 and nut 24. Member 22 has formed at right angles with said former hinge plate 5 another hinge plate 25 which lies between the arms of a clip 26 which are clamped against it to retain the arm at any required vertical adjustment by a screw 27.

The retaining means coöperating with the 10 spring-controlled hook comprises a swinging catch 28 which is adapted to engage a notch 29 in a bar 30 rigidly secured to a clip 31 on the standard. The catch is provided with an eye 32 through which the 15 bar passes and is normally retained in the engaging position by means of a spring 33 secured to the bar.

34 denotes a finger piece on the catch for convenience in operation.

20 The upper end of the swinging catch is provided with a head 35 which is pivoted as at 36 to a yoke 37 which is attached to the hook in any suitable manner, as by means of spring arms 38. Head 35 is also 25 pivoted as at 39 to swinging arms 40, in turn pivoted to a head 41 at the upper end of the bar, the arms in the present instance being shown as connected by a cross piece.

The operation will be readily understood 30 from the drawing. The receiver is adjusted at a convenient distance from the transmitter by moving sleeve 19 along arm 16 and locking it by set screw 20 after adjustment, and said arm is adjusted in both the 35 horizontal and vertical planes by means of the universal joint by which the inner end of the arm is connected to clip 26 on the standard. To open the circuit and retain it open it is of course necessary to retain the 40 hook in the position shown in Figs. 1 and 2; that is the position in which it is retained in ordinary telephones by the weight of the receiver. This is effected with my novel attachment by engagement of the 45 swinging catch with the notch in the bar, spring 33 acting to retain it in engagement. Suppose the parts to be in the position shown in Figs. 1 and 2 and the circuit open; to close the circuit for use the operator 50 is simply required to disengage the catch from the notch in the bar when the spring-controlled hook, shown in the present instance as controlled by spring 15, will move to the position shown in Fig. 3, that is the 55 closed circuit condition of the telephone. When the conversation is ended the circuit may be opened again by either moving the hook downward, or moving the swinging catch downward by means of the finger piece 60 until the catch engages with the notch in the bar. It will be noted that in closing the circuit for a conversation the operator merely disengages the swinging catch from the bar by a movement of the hand piece

in lieu of removing the receiver from the hook.

Having thus described my invention I claim:

1. A device of the character described comprising a notched bar, means for attaching said bar to a telephone standard, a swinging catch adapted to be pivotally connected to a telephone hook and to engage the notch in the bar and an arm for pivotally connecting the catch to the bar. 75

2. A device of the character described comprising a notched bar, means for attaching said bar to a telephone standard, a catch adapted to engage the notch, a yoke to which the catch is pivoted and swinging 80 arms pivotally connected to the catch and to the bar.

3. A device of the character described comprising a notched bar, means for attaching said bar to a telephone standard, a catch 85 adapted to engage the notch, a yoke to which the catch is pivoted, swinging arms pivotally connected to the catch and to the bar and a spring to retain the catch in the engaging position. 90

4. The combination with a telephone standard and a spring-controlled hook, of a notched bar, means for attaching said bar to the standard, a swinging catch, means for pivotally connecting said catch to the 95 hook, a swinging arm connecting the catch with the bar and a spring acting to retain the catch in engagement with the notch.

5. An attachment of the character described comprising a rigid bar provided 100 with a notch, means for attaching said bar to a telephone standard, a catch provided with an eye through which the bar passes, means for pivotally connecting said catch to a telephone hook and a swinging arm 105 pivoted to the bar and to the catch.

6. An attachment of the character described comprising a rigid bar, means for attaching said bar to a telephone standard, a catch provided with an eye through which a bar passes, means for pivotally connecting said catch to a telephone hook, a swinging arm pivoted to the bar and to the catch and a spring acting to retain the catch in engagement with the bar. 110

7. An attachment of the character described comprising a bar provided with a notch, means for attaching said bar to a telephone standard, a catch adapted to engage the bar and provided with a head, a yoke to which said head is pivoted, means for attaching said yoke to a telephone hook and a swinging arm pivoted to the bar and to the head of the catch. 115

8. An attachment of the character described comprising a bar provided with a notch, means for attaching said bar to a telephone standard, a catch adapted to 120

- gage the notch and provided with a hand piece, means for pivotally connecting said catch to a telephone hook and a pivotal connection intermediate said catch and the bar.
- 5 9. An attachment of the character described comprising a bar, means for attaching said bar to a telephone standard, a catch adapted to engage said bar, means for pivotally connecting said catch to a telephone hook, means for pivotally connecting said catch to the bar and a spring bearing against the catch.
- In testimony whereof I affix my signature in presence of two witnesses.

JOHN FRITH.
